TEMPERATURE SENSITIVE SWITCH

Morris Acker, Herbert Acker, Sidney Weitz, and Sidney J. Meistrich, Asbury Park, N. J.

Application December 11, 1952, Serial No. 325,474

4 Claims. (Cl. 200—142)

This invention relates to a temperature sensitive switch and particularly to a switch to be utilized in temperature responsive alarm systems.

In the construction and utilization of temperature alarm systems it is desirable to have a relatively simple inexpensive switch so that switches may be distributed as desired over the territory to be protected by the system without incurring a great expense.

The present invention provides an insulating body having channels along the opposed edges thereof so that terminal plates may be mounted in the channels and a recess in the face of the body extending intermediate the channels so that conductors attached to the terminal plates may extend in spaced relation across the bottom of the recess. A bridging element of the resilient spring biased type is mounted on a cover in the recess and retained out of contact with the conductors extending thereacross by means of a fusible joint which will fuse in response to the predetermined temperature to allow the switch member to be forced into contact with the conductors extending across the recess.

It is accordingly an object of the invention to provide an improved thermoresponsive switch.

It is a further object of the invention to provide a thermoresponsive switch having terminal plates recesses in the sides thereof.

It is a further object of the invention to provide a thermoswitch having a recess with spaced apart conductors mounted therein.

A further object of the invention is to provide a thermoresponsive switch having a spring biased switching element held out of contact with a pair of spaced apart conductors.

Other objects and many of the attendant advantages of the present invention will be apparent from the following detailed description taken in conjunction with the accompanying drawing in which:

Figure 1 is an exploded perspective of the thermoresponsive switch according to the invention;

Figure 2 is a vertical section through the top of the switch taken substantially on the plane indicated by the line 2—2 of Figure 1;

Figure 3 is a cross-section through the switch body taken substantially on the plane indicated by the line 3—3 of Figure 1;

Figure 4 is a vertical section taken substantially on the plane indicated by the line 4—4 of Figure 1;

Figure 5 is a cross-section through the switch anchor taken substantially on the plane indicated by the line 5—5 of Figure 2;

Figure 6 is a sectional elevation of the switch in closed position;

Figure 7 is a transverse section taken substantially on the plane indicated by the line 7—7 of Figure 4; and,

Figure 8 is a circuit diagram showing one method of utilizing the switch according to the invention.

In the exemplary embodiment of the invention a substantially rectangular insulating body 10 is provided with

2

opposed channels 12 and 14. Terminal blocks 16 and 18 are mounted in the respective channels 12 and 14. A recess 20 is provided in the top face of the body 10 and extends downwardly between the channels 12 and 14 but 5 in spaced insulated relation thereto. Preferably the bottom of the recess 20 is of arcuate formation as shown at 22. The terminal plates 16 and 18 are provided with anchor extensions 24 and 26 respectively. Anchor extensions being substantially tubular and extending into the 10 body 10 so that they extend transversely of the recess of aperture 20. The upper surfaces of the anchor members 24 and 26 are provided with flat surfaces 28 and 30 for a purpose presently to be described.

The terminal plate 16 is provided with a tubular anchor 15 extension 32 and the terminal plate 18 is provided with an anchor tube 34. The anchor tubes 32 and 34 extend in bores 36 and 38 which extend through the body 10. The bore 36 terminates in spaced relation to the channel 14 and is provided with a counter-bore 40 so that the end of 20 the tubular anchor extension 32 may be peened over or headed as shown at 42 to maintain the terminal plate 16 in fixed relation in the channel 12. Likewise the bore 38 is provided with a counter-bore 44 so that the end of the tubular anchor member 34 may be headed at 46 in spaced 25 relation to the channel 12 so that the terminal block 18 is rigidly maintained in the channel 14. The anchor members 32 and 34 are provided with threaded internal cavities so that fastening screws 48 may be extended therein for connecting conductors 50 thereto. The conducting 30 extensions 24 and 26 are likewise provided with internal threads so that screw fasteners 52 may be applied thereto for securing the conductors 54 thereto.

A cap 60 of substantially flat formation having downturned edges 62 and 64 and downturned end members 66 35 and 68 is provided for contact with the face of the block 10 in which is located the recess 20. The end of the block 10 is provided with recesses 70 and 72 adjacent the top edge thereof and the ends 66 and 68 are provided with spring detents 76 and 78 for cooperation with the recesses 40 72 and 74 to retain the cap 60 firmly in position on the top surface of the body 10. The cap 60 is provided with a substantially central aperture 80 for a purpose presently 45 to be described. A bridging member 82 preferably constructed of resilient material is provided in arcuate formation having ends bearing against the underside of the cap 60 having a bracket 86 rigidly secured adjacent the central portion thereof. The bracket 86 extends through the aperture 80 and is held in place by means of a fusible 50 material 88. Fusible material 88 being applied while the spring edging member 82 is in compressed relation so that the material 88 retains the bridging member in spaced relation from the conductors 24 and 26.

A clip base 90 includes a base member 92 having a plurality of apertures for receiving mounting screws 94. End members 96 and 98 extend upwardly to receive the 55 ends of the block 10 which is provided with recesses 100 and 102 for cooperation with detents 104 and 106 so that the body 10 may be snapped into the base member 90 and frictionally retained therein. End members 96 and 98 are provided with cut-out portions such as 108 and 110 for the passage of the conductors 50 and 54. Side members 112 and 114 are provided for extending along the sides of the body 10 for covering the channels 12 and 14.

While the switch as described may be utilized in many 60 systems of alarms or indicators, the useful system as indicated in Figure 8 where the conductors 50 and 54 are connected to the blocks 14 and 12 of the body 10. As indicated, a plurality of bodies 10 may be mounted in parallel circuit relation by continuing the conductors 50 and 54 or applying new conductors 50 and 54 to the opposite 65 ends of the terminal plates 12 and 14. Potential from any suitable source may be applied to the conductors 50 and

54 and a responsive device such as the magnetic device 120 is connected in one of the conductors such as the conductor 20. A rather high impedance 122 is connected across the open end of the circuit so that a relatively low current is drawn through the conductors 50 and 54 and the armature 124 which cooperates with the contact 126 is mounted at one end of the magnetic core 120 so that the normal current flowing through the system because of the impedance 122 will be sufficient to lift the armature 124 off of the contact 126. In the event the circuits should be broken so that no current flows therein the armature 124 would make contact with a terminal 126 and energize a signal such as the bell 128. The second armature 130 is biased from closing contact with the contact 132, the bias being sufficient to overcome the attraction produced by the current in the impedance 122. However, if an over temperature should arise so that the bridging member 82 should bridge the conductors 24 and 26, the heavy current would draw the armature 130 into contact with the terminal 132 and energize a second signal device such as the bell 140.

It will thus be apparent that the present switch is of low cost, easy to apply and simple in operation so that a large number of the switches may be conveniently applied in any desired circuit and preferably in a circuit so that the circuit will constantly be tested for continuity and also be continuously responsive to over-temperature in any portion of the circuit for giving an alarm or indication thereof.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to.

What is claimed as new is as follows:

1. A thermosensitive switch comprising an insulating body, said body having channels in opposed sides thereof, said body further having a cavity extending in spaced parallel relation intermediate said channels, terminals secured in said channels, a conductor secured to each of said terminals, said conductors extending in spaced relation in said cavity, a bridging conductor supported in said cavity, said bridging contact being biased to move into bridging relation with said conductors, fusible means restraining said bridging conductor from moving into bridging relation with said conductors, a cap removably secured on said body, said cap having an aperture therein, an anchor member on said bridging conductor, said anchor member extending into said aperture, said fusible means securing said anchor member in said aperture.

2. A thermosensitive switch comprising an insulating body, said body having channels in opposed sides thereof, said body further having a cavity extending in spaced parallel relation intermediate said channels, terminals secured in said channels, a conductor secured to each of said terminals, said conductors extending in spaced relation in said cavity, a bridging conductor supported in said cavity, said bridging conductor being biased to move into bridging relation with said conductors, fusible means restraining said bridging conductor from moving into bridging relation with said conductors, a cap removably secured on said body, said cap having an aperture therein, an anchor member on said bridging conductor, said anchor member extending into said aperture, said fusible means securing said anchor member in said aperture, said bridging conductor being an arcuate spring.

3. A thermosensitive switch comprising an insulating body, said body having channels in opposed sides thereof, said body further having a cavity extending in spaced parallel relation intermediate said channels, terminals secured in said channels, a conductor secured to each of said terminals, said conductors extending in spaced relation in said cavity, a bridging conductor supported in said cavity, said bridging conductor being biased to move into bridging relation with said conductors, fusible means restraining said bridging conductor from moving into bridging relation with said conductors, said terminals being longitudinally extending plates, anchor means on each of said terminals, said anchor means extending into and being secured in said body, the anchor means for said terminals being at opposed ends of said body.

4. A thermosensitive switch comprising an insulating body, said body having channels in opposed sides thereof, said body further having a cavity extending in spaced parallel relation intermediate said channels, terminals secured in said channels, a conductor secured to each of said terminals, said conductors extending in spaced relation in said cavity, a bridging conductor supported in said cavity, said bridging conductor being biased to move into bridging relation with said conductors, fusible means restraining said bridging conductor from moving into bridging relation with said conductors, an attaching plate resiliently receiving said body, side members on said attaching plate extending over said side channels.
